(57) **CLAIM**

The ornamental design for a chair, as shown and described.

DESCRIPTION

FIG. 1 is a front perspective view of a chair embodying my new design (with or without the handle shown in phantom). FIG. 2 is a front elevational view of the design.

FIG. 3 is a side elevational view of the design (with or without the handle shown in phantom), the opposite side being a mirror image thereof.

FIG. 4 is a rear elevational view of the design; and, FIG. 5 is a top plan view of the design.

The broken line showing of the handle is for illustrative purposes only and forms no part of the claimed design.
